UNITED STATES PATENT OFFICE

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF HIGHWAY-CROSSING SIGNALS

Application filed March 18, 1930. Serial No. 436,841.

My invention relates to apparatus for the control of highway crossing signals, and has for an object the provision of means for controlling signals of this character without the necessity for continuous track circuits. In accordance with one form of my invention, the necessity for track circuits is eliminated entirely.

10 I will describe two forms of apparatus embodying my invention, and will then point out the novel features thereof in claims.

In the accompanying drawing, Fig. 1 is a diagrammatic view showing one form of apparatus embodying my invention, in which form the necessity for track circuits is avoided. Fig. 2 is a view showing a modification of the apparatus shown in Fig. 1 and also embodying my invention, but requiring short 20 isolated track sections for the control of the highway crossing signal.

Similar reference characters refer to similar parts in each of the views.

Referring first to Fig. 1, the reference characters 1 and 1^a designate the track rails of a railway track A, which track is intersected by a highway H. Located at the intersection of the railway track and the highway is a 25 highway crossing signal S, which as here shown, is in the form of an electric bell.

Located to the left of the highway H is a light sensitive cell C¹, which normally receives light from a lamp L¹, these elements being so disposed that the supply of light to the cell C¹ is discontinued when a train or 35 car passes between the elements. Preferably the lamp and the cell are disposed on opposite sides of the track at about the level of the axles of a car, and are diagonally disposed with respect to the track, so that the supply 40 of light to the cell C¹ is continuously cut off during the passage of a car. The cell C¹ comprises an enclosing tube which is open at the end toward the track, in order to prevent the 45 light sensitive element of this cell from being influenced by light other than that which is received from the lamp L¹. Similarly, the lamp L¹ comprises an enclosing tube which is open at the end toward the track and the 50 inner end of which constitutes a reflector.

Other cells C², C³ and C³₁ are disposed along the track between the cell C¹ and the highway H, and are arranged to be normally supplied with light from lamps L², L³ and L³₁, respectively. Located at the highway H is another light responsive cell C⁴ normally receiving light from the lamp L⁴, but so arranged that the light from this lamp is discontinued during the passage of a car. Each 55 lamp and its associated cell may be similar to the elements now commonly employed to control street traffic signals.

The signal S is controlled by two normally energized relays E and F, the former of which 60 preferably comprises two windings 18 and 19. Winding 18 of relay E is provided with a stick circuit which passes from terminal B of a suitable source of current, through cell C², front contact 8 of relay E, and winding 18 65 of this relay to terminal O of the same source of current. This winding is also provided with a pick-up circuit which passes from terminal B, through the cell C², front contact 12 of relay F, and winding 18 to terminal O. Winding 19 of relay E is provided with a 70 holding circuit which passes from terminal B, through front contact 9 of relay E, winding 19 of this relay, and back contact 13 of relay F to terminal O. 75

80 Relay F is provided with a stick circuit which passes from terminal B, through cell C³, front contact 11 of relay F, and the winding of this relay to terminal O. This circuit is provided with a branch around the cell C³, 85 which includes cell C³₁, so that relay F will become deenergized when and only when both of the cells C³ and C³₁ are dark. These cells are placed close enough together to insure that they will both be darkened at the 90 same time by a passing train. The reason for providing two cells for the control of relay F, is to prevent this relay from being deenergized by a person walking along the track. Momentary darkening of the other cells will 95 not disarrange the apparatus.

A third relay G is provided with a circuit which includes cell C⁴, whereby this relay is normally energized but becomes deenergized while a train is passing the highway H. As 100

sociated with relay G is a normally deenergized slow-releasing relay M provided with a circuit which includes a back contact 15 of relay G. It follows that when a train passes highway H, relay M will become energized while relay G is deenergized, whereupon after relay G again becomes energized, the front contacts of relay M will remain closed for a brief interval of time.

10 Relay F is provided with a pick-up circuit which passes from terminal B, through the cells C³ and C³₁ in multiple, front contact 16 of relay G, front contact 17 of relay M, and the winding of relay F to terminal O.

15 Another relay D is provided with a circuit which includes cell C¹, and another slow-releasing relay K is provided with a circuit which includes back contact 5 of relay D. Relay F is provided with a second pick-up circuit which includes front contact 6 of relay D, and front contact 7 of relay K in series.

The signal S is provided with a circuit which passes from terminal B, through back contact 10 of relay E, back contact 14 of relay F, and the signal S to terminal O. It follows that this signal will operate when and only when both relays E and F are de-energized.

30 The operation of the apparatus shown in Fig. 1, is as follows:

Normally all of the relays except K and M are energized, so that the signal S is inactive. While a train moving toward the right is passing the cell C¹, it will deenergize relay D, and this will energize relay K, but the operation of these relays has no effect on the rest of the apparatus. When the train passes cell C², it will reduce the current in both the stick and the pick-up circuits for relay E to such value that this relay will release. Then before the train loses its influence on cell C², it will obscure cells C³ and C³₁, thereby reducing the current in the stick circuit for relay F to such an amount that this relay, likewise, will release. Relay F will then stay open, because both of its pick-up circuits are open, and relay E will stay open because its pick-up circuit is open at contact 12 of relay F. Relays E and F both being open, the signal S will operate to indicate that a train is approaching the highway H. When the train passes the highway, it will deenergize relay G, and this will energize relay M; then during the brief interval of time in which contacts 16 and 17 of these relays are both closed, one of the pick-up circuits for relay F will be closed, so that this relay will again become energized. The closing of contact 12 of relay F will close the pick-up circuit for relay E, so that the latter relay will, likewise, become energized. The operation of the signal S will therefore be discontinued, and the parts of the apparatus

will be restored to the conditions in which they are shown in the drawing.

When a train moves in the other direction, that is, toward the left, it will deenergize relay G when it passes the highway H, and this will energize relay M, but this operation of relays G and M will have no effect on the other parts of the apparatus. When the train obscures both cells C³ and C³₁, relay F will release, thereby closing the holding circuit for winding 19 of relay E at back contact 13 of relay F. It follows that when the train obscures cell C², relay E will remain energized, because this holding circuit remains closed. Consequently, signal S will not be set into operation because its circuit will remain open at back contact 10 of relay E. When the train passes cell C¹, the second pick-up circuit for relay F will become closed, so that this relay will become energized, and all parts of the apparatus will be restored to the conditions in which they are shown in the drawing.

Referring now to Fig. 2, the apparatus shown in this view is the same as that shown in Fig. 1, except that short insulated track sections are substituted for the light responsive cells for the control of relays D, E, F and G. Three short sections P¹, P² and P³ are located to the left of the highway H, and a fourth section P⁴ is located at the highway, these sections being formed by insulated joints 2 in one of the rails 1^a. Each section is provided with a source of current connected across the rails 1 and 1^a, this source being represented by the terminals B and O. Relay D is connected across the rails at section P¹, and relay G is connected across the rails at section P⁴. Winding 18 of relay E is connected across the rails at section P², through front contact 8 of this relay and contact 12 of relay F in multiple, so that relay E is provided as in Fig. 1 with a stick circuit and a pick-up circuit. The holding circuit for winding 19 of relay E is the same as in Fig. 1. Relay F is connected across the rails at section P³ through its own front contact 11, so that this relay is provided with a stick circuit as in Fig. 1. The two pick-up circuits for relay F are the same as in Fig. 1, and the circuit for the control of signal S, is, likewise the same as in Fig. 1. The operation of the apparatus shown in Fig. 2 will be obvious from the foregoing explanation of the operation of the apparatus shown in Fig. 1.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a railway track intersected by a highway, two normally energized relays E and F, a stick circuit for relay E including its own front contact, a pick-up circuit for relay E including a front contact of relay F, a holding circuit for relay E including its own front contact and a back contact of relay F, a stick circuit for relay F including its own front contact, a normally energized relay G, a slow-releasing relay M controlled by a back contact of relay G, a pick-up circuit for relay F including front contacts of relays G and M in series, means controlled by a train approaching said highway for reducing the current in the stick and pick-up circuits for relay E to open this relay and for subsequently reducing the current in the stick circuit for relay F to open the same before relay E can close, means controlled by such train when it reaches the highway for causing relay G to release, and a highway crossing signal controlled by said relays E and F. 70
2. In combination, a railway track intersected by a highway, two normally energized relays E and F, a stick circuit for relay E including its own front contact, a pick-up circuit for relay E including a front contact of relay F, a holding circuit for relay E including its own front contact and a back contact of relay F, a stick circuit for relay F including its own front contact, a normally energized relay G, a slow-releasing relay M controlled by a back contact of relay G, a pick-up circuit for relay F including front contacts of relays G and M in series, means controlled by a train approaching said highway for reducing the current in the stick and pick-up circuits for relay E to open this relay and for subsequently reducing the current in the stick circuit for relay F to open the same before relay E can close, means controlled by such train when it reaches the highway for causing relay G to release, a normally energized relay D, a slow-releasing relay K controlled by a back contact of relay D, a second pick-up circuit for relay F including front contacts of relays D and K in series, means controlled by a train moving away from said highway for causing relay D to release after the train has passed the locations wherein relays E and F are influenced, and a highway crossing signal controlled by said relays E and F. 80
3. In combination, a railway track intersected by a highway, three sources of light disposed along the railway, three light responsive cells C², C³ and C³₁ normally receiving light from said three sources respectively but arranged to be successively obscured by a train approaching said highway, two relays E and F, a stick circuit for relay E including a front contact thereof and cell C², a pick-up circuit for relay E including cell C² and a front contact of relay F, a holding circuit for relay E including a front contact thereof and a back contact of relay F, a stick circuit for relay F including a front contact thereof and cells C³ and C³₁ in multiple, a fourth source of light and a fourth light responsive cell C⁴ normally receiving light therefrom but obscured when a train is adjacent said highway, a relay G provided with a circuit including cell C⁴, a slow-releasing relay M controlled by a back contact of relay G, a pick-up circuit for relay F including front contacts of relays G and M in series, and a highway crossing signal controlled by relays E and F. 85
4. In combination, a railway track intersected by a highway, three sources of light disposed along the railway, three light responsive cells C², C³ and C³₁ normally receiving light from said three sources respectively but arranged to be successively obscured by a train approaching said highway, two relays E and F, a stick circuit for relay E including a front contact thereof and cell C², a pick-up circuit for relay E including cell C² and a front contact of relay F, a holding circuit for relay E including a front contact thereof and a back contact of relay F, a stick circuit for relay F including a front contact thereof and cells C³ and C³₁ in multiple, a fourth source of light and a fourth light responsive cell C⁴ normally receiving light therefrom but obscured when a train is adjacent said highway, a relay G provided with a circuit including cell C⁴, a slow-releasing relay M controlled by a back contact of relay G, a pick-up circuit for relay F including front contacts of relays G and M in series, a fifth source of light and a fifth light responsive cell C¹ arranged to be obscured by a train moving away from the highway after it has influenced cell C², a relay D provided with a circuit including cell C¹, a slow-releasing relay K controlled by a back contact of relay D, a second pick-up circuit for relay F including front contacts of relays D and K in series, and a highway crossing signal controlled by relays E and F. 90
5. In combination, a railway track intersected by a highway, said track being provided with three short insulated sections P¹, P² and P³ arranged to be bridged successively in the order named by a train approaching the highway, and with a fourth section P⁴ located adjacent the highway, a source of current connected across the rails of each section, two relays D and G connected across the rails of sections P¹ and P³ respectively, a relay F having a winding connected across the rails of section P³ through a front contact of the relay itself, a relay E having a winding connected across the rails of section P² through a path which includes a front contact of the relay itself and a front contact of relay F in multiple, a holding circuit for relay E including a front contact thereof, and a back 100

- contact of relay F, two slow-releasing relays K and M controlled by back contacts of relays D and G, respectively, two shunts for the circuit of relay F around the front contact thereof, one of which shunts includes front contacts of relays G and M in series and the other of which includes front contacts of relays D and K in series, and a highway crossing signal controlled by said relays E and F.
6. In combination, a railway track intersected by a highway, two normally energized relays E and F, means controlled by a train approaching the highway for first deenergizing relay E and for subsequently deenergizing relay F before its influence over relay E ceases, means for preventing relay E from becoming reenergized until relay F again becomes energized, means controlled by such train when it reaches the highway for re-energizing relay F, means responsive to the prior deenergization of relay F when a train moves in the other direction for preventing relay E from being deenergized by such train, means controlled by a train moving in the last-mentioned direction for reenergizing relay F after it has passed the points at which said relays are influenced, and a highway crossing signal set into operation when and only when relays E and F are both de-energized.

In testimony whereof I affix my signature.
LARS O. GRONDAHL.
